UNITED STATES PATENT OFFICE

2,356,629

ELECTRICAL REGULATOR

Jerry L. Stratton, Schenectady, N. Y., assignor to
General Electric Company, a corporation of
New York

Application May 8, 1941, Serial No. 392,416

3 Claims. (Cl. 171—223)

This invention relates to electrical regulators and more particularly to improvements in automatic variable-resistance-type electrical regulators.

Automatic variable-resistance-type regulators are commonly used to maintain constant automatically an electrical condition such as the voltage of a dynamo electric machine. In some classes of service the speed of the dynamo electric machine is constant, whereas in other classes of service, such as vehicles whose speed is variable, the speed of the dynamo electric machine varies so that the duty imposed on the regulator is more severe in that it has to counteract the additional effect of changes in speed as well as the common effect of changes in load on the voltage of the machine. The trend is toward the use of larger and larger amounts of electrical energy on vehicles, thus requiring larger and larger size generators to supply the load and in certain classes of service, such as in airplanes, weight is an important factor, so that in such service the duty on the regulator is increasing while it is desirable that the weight of the regulator be kept as low as possible.

In accordance with this invention there is provided a novel and simple resistance-type regulator which is relatively low in weight in comparison with the amount of current which it can control. It is characterized by the use of a plurality of spring contact fingers connected respectively to taps in fixed resistors, the contact fingers all making contact with a common conducting element for short circuiting the resistor and being moved out of contact with the common conducting element successively so as to increase the effective value of the resistance. In this manner each contact finger normally handles only a small portion of the total resistor current and the various contact resistances are in parallel rather than in series.

An object of the invention is to provide a new and improved electrical regulator.

Another object of the invention is to provide a low-weight high-capacity automatic resistance regulator.

This invention will be better understood from the following description taken in connection with the accompanying drawing and its scope will be pointed out in the appended claims.

In the drawing Fig. 1 is a front elevation of an embodiment of the regulator, Fig. 2 is a side elevation of the regulator shown in Fig. 1 when viewed from the right-hand end thereof, and Fig. 3 is a circuit diagram of the regulator connections 55

in which the essential elements of the regulator are shown in exaggerated perspective.

Referring now to the drawing, in which like elements will be designated by similar reference characters throughout the several views, the regulator is shown mounted on a suitable base 1 which is shown as substantially rectangular in shape and which may be made of any suitable material, such as aluminum. Mounted at the top of this support by means of studs 2 are four resistance sticks 3, 4, 5 and 6, these sticks being insulated from the studs and from each other by insulating spacers or washers 7. These resistance sticks are of conventional construction consisting of a coil of resistance wire embedded in suitable insulation, such as porcelain. They are each provided with a plurality of taps designated generally by the reference numeral 8.

Mounted beneath the resistance sticks is a bracket 9 which is fastened to the support by suitable screws 10 extending through the support. This bracket 9 carries or supports the rest of the regulator consisting of a contact assembly and an operating magnet. The contact assembly consists of two vertically spaced tiers of parallel contact fingers, each tier of parallel contact fingers being arranged in a horizontal plane. The upper set of contact fingers is shown at 11 and the lower set is shown at 12. The left-hand ends of the contact fingers 11, as viewed in Fig. 1, are embedded or clamped in an insulating block 13 and the left-hand ends of the contact fingers 12 are held in an insulating block 14. The right-hand or free ends of the contact fingers engage or make contact with a conducting member 15. Below the insulating member 14 is an electromagnet assembly 16 having a bracket 17 at its left-hand end. The bracket 17 is fastened to the bracket 9 by means of screws 18 which extend through the insulating members 13 and 14 and which serve to clamp them tightly. The common contact 15 for the spring contact fingers is supported by the right-hand end of the magnet assembly through extensions 19 on the member 15 and by means of screws 20.

The magnet 16 is provided with an armature 21 which is effectively pivotally mounted on a novel frictionless support. This support consists of a metal extension or plate 22 which is clamped between the insulating members 13 and 14. This has a flat upper surface with a straight line edge. The armature is carried by a frame 23 to which is attached a pair of spacer members 24 carrying at their upper ends projecting arms 25 which have flat end surfaces and straight

outer edges. The projections 25 are in overlapping relation to the edge of the surface 22 and flat blade springs 26 are mounted between the upper surface of 22 and the lower surfaces of 25 and have their ends fastened to these respective elements. In this manner the frame 23 and consequently the armature 21 is restrained from motion in any direction except one of rotation about an effective pivot along the axis created by the lines of contact of the members 22 and 25.

By reason of the location of this effective pivot with respect to the magnet and the armature, that is to say, by reason of the pivot being above the magnet and longitudinally between its ends, the armature 21 when attracted to the left-hand end of the magnet will have a downward component of motion as well as an inward component of motion, these components being those of the tangent of the circular path of the armature. As the flux produced by the magnet varies inversely with the distance from the center of its pole face, it will be seen that the inward motion of the armature toward the pole face and therefore toward a magnetic field of greater density will be offset by the downward component of the motion of the armature which is toward a lower density magnetic field. These two effects may be made to neutralize each other so that the magnetic pull on the armature is substantially independent of its position.

Fastened to the outer end of the frame 23 by means of arms 27 is a frame 28 of insulating material of the same general shape as the member 15 except that its two uppermost surfaces, corresponding respectively to the surfaces of the member 15 with which the separate tiers of contact fingers make contact, are inclined slightly with respect to those surfaces. Furthermore, the slopes of these two surfaces of the insulating member 28 are slightly different from each other, the slope of the topmost surface shown by the dotted line 29 in Fig. 2 being slightly greater than the slope of the lower surface 30.

By means of this construction the inward and downward motion of the armature 21 under the influence of the magnet pole of the magnet 16 will cause the insulating frame 28 to move upwardly whereby the left-hand contact finger of the lower tier will be moved upwardly and out of engagement with the conducting frame 15. The continued upward movement of the frame 28 will cause the left-hand contact finger of the upper tier to be moved out of contact with the member 15. Next the second contact finger from the left of the lower tier and then the second contact finger from the left of the upper tier, etc., zigzagging alternately between the upper and lower tiers will be moved out of contact with the conducting frame 15.

The pole of the magnet 16 is counterbalanced by a spring 31 whose upper end is fastened to an extension 32 on the frame 23 and whose lower end is fastened to a screw 33 provided with a knurled nut 34 whereby the spring tension and consequently the setting of the regulator may be adjusted. Undesirable vibration of the armature assembly is damped out by means of a dashpot 35 mechanically connected in parallel with the spring 31.

In Fig. 3 the regulator is shown connected as a voltage regulator for a direct current generator 36 which is provided with a pair of shunt field windings 37 and 38 and with a series winding 39 which may either be a compounding winding or a commutating winding. Resistors 3 and 5 are

connected in series with the shunt field winding 37 and resistors 4 and 6 are connected in series with the shunt field winding 38. The two left-hand contact fingers of the lower tier are connected to the first two taps of the resistance 6 and the next two contact fingers of the lower tier are connected to the first two taps of the resistor 4. In a like manner the first two left-hand contact fingers of the upper tier 11 are connected to the first two taps of the resistor 5 and the next two contact fingers of the upper tier 11 are connected to the first two taps of the resistor 3. While only four contact fingers have been shown in each tier in Fig. 3, it will be understood that actually there are a great many more contact fingers. For example, in Fig. 2 each tier is shown as consisting of ten contact fingers but in practice it is often desirable to employ more than this.

The main control coil of the regulator is shown as consisting of two serially connected windings 40 and 41 which are connected between the ungrounded terminal of the generator and ground so that they carry current proportional to the generator voltage. An auxiliary winding 42 is also provided on the magnet and this is connected to the ungrounded side of the series winding so as to have impressed upon it a voltage which is proportional to the current in the generator. The circuit of this winding is completed through a switch 43 for connection to an equalizer bus to which similar windings of other regulators are connected when it is desired to have the regulator control parallel-connected generators. Such a connection amounts to a differential voltage connection so that the machine carrying the higher current will have a higher series winding voltage and hence the current through the equalizer bus will be in such a direction as to cause the coil 42 on the high voltage generator to aid the main coils and cause the corresponding coil 42 on the low voltage generators to oppose their associated main coils so as to equalize the voltage and prevent circulating currents in parallel-connected machines.

The operation of the regulator system is such that the armature 21 is in a condition of equilibrium or balance between the opposing forces of the magnet 16 and the spring 31. If the voltage increases the armature is attracted, thereby raising insulating frame 28 and successively lifting contact fingers for engagement with the conducting member 15 thereby removing short circuits from increments of the resistors and thereby increasing the field resistance of the generator whereby its field current and consequently its voltage will decrease. Similarly, a decrease in generator voltage will cause the reverse action thereby short circuiting successive increments of the resistors and increasing the field strength.

The connections are such that substantially balanced or equal current is maintained in the two field windings and at the same time substantial balance or equal current is maintained in all of the four resistors although, of course, the resistor currents will be substantially one-half the field winding currents. As the maximum voltage tending to cause arcing at each contact finger is that produced by the voltage drop in a section of each resistor between adjacent taps and as the current in each resistor is but half the field current of its associated field winding and as this field current is only one-half the total field current required by the machine, it will be seen that relatively small and delicate contacts and contact

fingers will safely control a relatively large size generator.

While there has been shown and described a particular embodiment of this invention, it will be obvious to those skilled in the art that various changes and modifications can be made therein without departing from the invention and, therefore, it is aimed in the appended claims to cover all such changes and modifications as fall within the true spirit and scope of the invention.

What I claim as new and desire to secure by Letters Patent of the United States is:

1. In combination, a dynamo-electric generator having a plurality of field windings, a plurality of multi-tapped resistors connected respectively in circuit relation with said field windings, electroresponsive circuit making and breaking regulating mechanism for progressively short circuiting the taps of said resistors, and means included in said mechanism for causing said short circuiting to occur alternately in a predetermined sequence with respect to said resistors such that after a given small fraction of the number of taps have been short circuited in one resistor the same small fraction of the number of taps are short circuited a tap at a time in another resistor until the same number of taps are short circuited in all the resistors before an additional tap is short circuited in said one resistor.

2. In combination, a dynamo-electric generator having a field winding, a plurality of multi-tapped resistors connected in circuit with said field winding, electroresponsive circuit making and breaking 5 regulating mechanism for progressively short circuiting the taps of said resistors, and means included in said mechanism for causing said short-circuiting to occur alternately in a predetermined sequence with respect to said resistors such that 10 after a given number of taps have been short circuited in one resistor the same number of taps are short circuited a tap at a time in another resistor at a time until the same number of taps are short-circuited in all the resistors before an 15 additional tap is short circuited in said one resistor.
3. In combination, a dynamo-electric generator having a field winding, a plurality of multi-tapped resistors connected in circuit with said field winding, 20 a plurality of contacts, movable means for effecting sequential and cumulative interconnection of said contacts, said contacts being connected respectively to said taps in such a manner that said means makes connection to said resistors through the respective contacts for their 25 taps in a predetermined cyclic sequence.
